UNITED STATES PATENT OFFICE.

FREDERIC W. HILLARD, OF NEW YORK, N. Y., ASSIGNOR TO MARY R. HILLARD, OF MIDDLEBURY, CONNECTICUT.

TYPE-WRITING MACHINE.

1,139,035.

Specification of Letters Patent. Patented May 11, 1915.

Original applications filed August 25, 1898, Serial No. 603,845, and March 22, 1909, Serial No. 485,147. Divided and this application filed April 25, 1912. Serial No. 693,039.

To all whom it may concern:

Be it known that I, FREDERIC W. HILLARD, a resident of Tottenville, in the county of Richmond and city and State of New York, have invented certain new and useful Improvements in Type-Writing Machines, of which the following is a specification.

My present application is a division of my prior application filed August 25, 1898 and serially numbered 603,845, which was 10 patented on the 30th day of April, 1912, Patent Number 1,025,089; this application was divided out of said parent application in pursuance of requirement of division 15 made by the Patent Office; the subject matter here involved was then claimed in my divisional application Serial No. 485,147, filed March 22, 1909, and upon further requirement of division made therein by the Patent 20 Office the present case was filed.

My herein invention is an improvement in typewriting machines, and relates particularly to the ribbon feeding, carrying and operating mechanism.

My invention also relates to means in a typewriting machine for feeding the printing ribbon by aid of mechanism provided to resolve the pull of the carriage propelling power into a component effective for reciprocating the feed pawls; and also, in a visible writing typewriting machine to means whereby the ribbon is reciprocated to the printing point by the type keys and away therefrom by aid of the repulsive action of 35 the carriage propelling power.

It also relates to the combination of a repulsive escapement with the ribbon feeding and reciprocating mechanisms; and specifically to the combination of a roller dog escapement, with said ribbon mechanisms, whereby the repulser action of the main spring is transmitted through aid of the escapement roller to move or reciprocate the ribbon away from the printing point and 45 also to move or reciprocate the ribbon feeding pawls in one direction.

In the accompanying drawings, which form a part of the specification: Figure 1 is a sectional elevation with some of the parts 50 of the machine broken away or removed, and with a portion of the ribbon vibrating mechanism shown in full lines. Fig. 2 is a

side elevation, showing the carriage in its raised or lifted position. Figs. 3 to 7 are 55 positional detail views of the escapement mechanism, which coöperates with and assists in the movement of the ribbon. Figs. 3 and 6 show the parts in their normal or engaged position; Figs. 4 and 7 show them in the depressed key or disengaged position; 60 and Fig. 5 is a plan view of the dogs and the escapement roller after the release of the depressed key, while the carriage is feeding and the dogs are being reengaged or returned to normal position. 65

Fig. 1 shows a sectional view of the base frame 1. Extending in a perpendicular direction from the back portion of the base frame are the brackets 2 for the carriage guide rail 3 and the parts mounted on the guide rail. 70 The principal parts which are mounted on the guide rail are the platen carriage, 4, rack, 5, and the carriage shifting frame, 6. At the front of the machine is placed the key board. Intermediate between the carriage 75 and the key board the type bar plate, 7, is mounted on the base frame of the machine. The type bar plate inclines backward at a slight angle from the perpendicular. It comprises a ring with type bars mounted 80 concentrically thereon and pivoted so that they can all strike through the central opening to a common printing point on the platen 8. There is a central opening 85 through the casing 9 which guards the type bar plate. Through this central opening the writing on the platen may be clearly seen by the operator as soon as each letter has been printed.

The inking ribbon, 10, is mounted on the 90 spools, 11, and is fed from one spool to the other by the ratchets, 12, and the pawls, 13, which are connected with the dog carrying rocker frame 14. There are two stationarily mounted ribbon spools, one at each 95 side of the machine, and likewise two ratchets and two feeding pawls, 13. Each ribbon spool is mounted to revolve, together with its ratchet, 12, on the common shaft, 15, at each side of the machine. The ribbon 100 spool, and ratchet and their common shaft, at the left hand side of the machine, are shown in dotted lines, back of the casing, 9, in Fig. 1; and the right hand ribbon

spool, ratchet and shaft are shown in full lines in Fig. 2.

The two ribbon feed pawls, 13, are mounted respectively on the left hand and right hand ends of their common shaft, 16, to oscillate therewith, so that whichever pawl is in engagement with its ratchet, 12, will cause its spool shaft, 15, to revolve step by step, as the keys are operated, so as to alternately wind the ribbon first onto one spool and then the other.

Extending downwardly from rock shaft 16, there is a rocker arm, 17, in line with the dog rocker frame 14 and connected therewith by means of the connecting rod, 18, so that whenever the dog rocker is oscillated by the depression of the keys, 19, in writing, the rock shaft 16 and ribbon feed ratchet pawls, will be oscillated therewith, thus feeding the ribbon each time the keys are operated. The ribbon passes through the ribbon guide or holder, 20, and the ribbon guide is pivoted to arm or support, 21, near its lower end, said arm being rigidly attached to the stationary machine frame, and serving as a fulcrum upon which the ribbon guide oscillates. At its lower end the ribbon guide is connected to connecting wire, 22, which latter extends back to and is connected with the dog rocker frame 14.

The key levers, 23, are provided at their front ends with the keys 19, are fulcrumed intermediately on fulcrum bar 24 and the keys are normally held up by the key lever springs, 25, which hold down the rear ends of the key levers. At their rear ends the key levers underlie the universal bar, 26, which latter is rigidly fastened on the dog rocker.

40 The carriage is mounted upon and fastened to the guide rail 3 by race ways and bearing balls in the guide rail and carriage, as shown; and it is also supported on the front rail 27, when in writing position, by means of the roller, 28. The carriage main spring is contained in the spring barrel, 28^a, which latter is connected to the carriage by means of connecting strap, 29. The carriage is adapted to travel on the guide rail 50 and front rail from one end of the rails to the other but is normally held in check by the engagement of the rack 5 with the normally engaging dog, 30.

The operation of the machine is as follows: Upon depression of a key 19, the connected type bar, or printing member, 31, is swung to the platen to print, by means of the train of connections comprising, with the key lever, the key lever connecting wire, 32, bell crank, 33, and type bar connecting wire, 34. At the same time the universal bar 26 is swung upwardly by the key lever and oscillates the dog rocker and dogs forwardly, thus disengaging the normally engaging dog 30 and engaging the normally

disengaged dog, 35, with the rack. The forward swinging of the dog rocker, during the depression of the key, also serves by means of connecting wire 22, to move the ribbon guide 20 and the ribbon therein from the normal position shown in Figs. 1 and 2, to the printing point at the platen. Normally the ribbon is out of the line of vision between the operator and the printing point at the platen, as indicated by the arrow pointing to the printing point in Fig. 1.

Upon release of the depressed key the key lever spring 25 exerts its force to lift the key and to restore the connected type bar to its position of rest in the basket. The force of the main spring, at the same time feeding the carriage forward along the rails, causes the wing 36 of dog 35 to run down the escapement roller 37, thereby swinging the escapement rocker, 14, rearwardly and thus disengaging the dog 35 from the rack and reengaging dog 30 therewith, and also, by the backward rotation of the dog rocker, swinging the ribbon carrier 20 and ribbon therein away from the printing point and out of the line of vision between the operator and the platen, as well as assisting in lifting the depressed key and restoring the type bar into its position of rest in the basket. The force of the main spring thus applied to the escapement rocker, and through the rocker to the other moving parts, to restore them to their normal positions or start them back from the printing point, as above described, has come to be known in the art as "repulsion;" and I accordingly use that term herein as indicating such impulse by the carriage propelling power. At the same time, also, the main spring, by causing the backward oscillation of the dog rocker, oscillates the connected rocker arm and rocker bar 17, and 16, and therefore oscillates the ribbon ratchet feed pawls in one direction. It is thus obvious that the ribbon feed ratchet pawls are oscillated in one direction by the blow of the operator on the key and in the other direction by the force of the main spring, to feed the ribbon as the machine is operated.

I wish to call attention that in my present structure the repulsive action of the main spring may be exerted upon the type bar, at the printing point, in two ways, after the release of the depressed key. First; it may be transmitted through the escapement rocker to the depressed key lever and thence, through the connecting wires 32 and 34 and the bell crank lever 33, to the short arm of the type bar which is attached to the connecting wire 34. Or, second; it may be transmitted through the connecting wire 22 and ribbon holder 20 and the interposed ribbon therein, directly to the type at the printing point. Regarding the first method of transmission it is obvious that, owing to

115

120

125

130

the several connections between the key lever and type bar in my present machine, and the necessary looseness in the several joints, that there is liable to be a perceptible delay in the transmission of the repulsion from the escapement to the type bar; and that this may result in the type remaining too long at the platen, while the carriage feed is beginning. Such sluggishness in the 10 starting away of the type bars from the platen will, obviously, endanger blurring in the print, particularly since the machine herein is a visible writing typewriter, wherein the type bars strike at the front of the platen, so that gravity does not assist 15 in starting back the type bars from the printing point. On the contrary gravity rather acts to maintain many of the type bars at the platen. Regarding the second 20 method of transmission, namely through the ribbon mechanism and ribbon directly to the type, it is obvious that any repulsion thus transmitted will instantly start the type bar away from the platen, because 25 there is nothing to resist such repulsion, the depressed key being released before the repulsion can be transmitted. Hence it is clear that the result which flows from my present combination of elements, is an improvement over that which would be obtained were the ribbon repulsion to be eliminated from the combination.

I believe myself to be broadly the first to have provided means whereby the force of 35 the main spring for propelling the carriage was resolved into a component effective to repulse the keys, and start back the escapement after the printing; and I also believe myself the first to have so connected up 40 the ribbon reciprocating and feeding mechanisms with a repulsive escapement as that the ribbon was started away from the printing point after the printing, to expose the writing to view, by the repulser action of 45 the main spring, and also whereby the ribbon feeding pawls are reciprocated in one direction by the said repulser action. I therefore claim broadly herein, in a typewriter machine, the combination of a repulser 50 escapement and ribbon feeding mechanism actuated thereby through the repulsive component of the main spring; and I also claim broadly herein, in a typewriter 55 having its printing point normally in view, the combination with a repulser escapement, of ribbon reciprocating mechanism, moved to the printing point by the keys, and away therefrom by aid of the repulsive component 60 of the main spring.

In discussing the escapement mechanism herein and where I include that mechanism in the accompanying claims, I use language and terms similar to those used in my prior broad repulser Patent No. 580,281 patented 65 April 6, 1897; and I intend to give such

language and terms herein the same meaning herein as similar language comprised in said prior broad repulser patent.

Since, at the date of this application, various ribbon feeding mechanisms and in 70 visible writing typewriting machines, various reciprocating mechanisms, were known to the art, I do not wish to limit myself to the specific mechanisms shown, but wish it understood that I intend to include in 75 the claims the various forms of such mechanisms known to the art.

Having thus described my invention, what I claim and desire to secure by Letters Patent is:

1. In a typewriting machine, the combination of type keys, carriage propelling power, and a pawl and ratchet ribbon feed, means operated by the stroke on the keys for reciprocating the ribbon pawl in one 85 direction, and means operated by the carriage propelling power for reciprocating the ribbon pawl in the other direction, substantially as described:

2. In a typewriting machine, the combination of type keys, carriage propelling power, a letter spacing escapement comprising two engaging members which can be disengaged and reengaged and a pawl and ratchet ribbon feed, means operated by the 90 stroke on the keys for disengaging the escapement members and reciprocating the ribbon pawl in one direction, and means operated by the carriage propelling power for 95 reengaging the escapement members and reciprocating the ribbon pawl in the other direction, substantially as described.

3. In a typewriting machine, the combination of ribbon actuating mechanism, carriage propelling power, an escapement, and 105 means for transmitting the carriage propelling power through the escapement to the ribbon actuating mechanism, and for thereby actuating the ribbon mechanism by the carriage propelling power, substantially 110 as described.

4. In a typewriting machine, the combination of type keys, carriage propelling power, a letter spacing escapement comprising a spaced member and a spacing member, 115 and a pawl and ratchet ribbon feed, means operated by the keys for disengaging the normally engaging parts in the escapement and reciprocating the ribbon pawls in one direction, and means operated by the carriage propelling power through the spaced member of the escapement for reengaging said normally engaging parts in the escapement and reciprocating the ribbon pawls in 120 the opposite direction, substantially as described.

5. In a typewriting machine which has its printing point normally in view and the printing ribbon normally away therefrom, the combination of keys and means operated 130

by the keys for moving the printing ribbon to the printing point, and carriage propelling power and means operated thereby for starting said ribbon back to its normal position.

6. In a typewriting machine which has its printing point normally in view and the printing ribbon normally away therefrom, the combination with the carriage and type bars, of an escapement having two engaging members which can be disengaged and reengaged, keys and means operated thereby for disengaging said members and moving the printing ribbon and type bars to the printing point, and carriage propelling power and means operated thereby for reengaging said members and starting the ribbon and type bars back to normal position.

7. In a visible writing typewriting machine, the combination with the type keys, type bars, carriage and carriage propelling power, of an escapement comprising two engaging members which can be disengaged and reengaged, a printing ribbon, a pair of stationarily mounted spools on which the ribbon is wound, means for alternately winding the ribbon upon each spool, a movable ribbon guide arranged and adapted to hold a portion of the ribbon adjacent the printing point but normally to one side of the visual line between the operator and the print, means operated by the type keys for disengaging the escapement members and for moving the ribbon guide and ribbon and type bars to the printing point to print, and means operated by the carriage propelling power for reengaging the escapement members and for repulsing the ribbon guide and ribbon and the type bars away from the printing point.

8. In a front strike typewriter which has its printing point normally in view, the combination with the type keys, type bars, carriage and carriage main spring, of a printing ribbon, a pair of stationarily mounted spools on which the ribbon is alternately wound, a movable ribbon guide adapted to hold a portion of the ribbon adjacent the printing point, means operated by the type keys for moving the ribbon

guide and ribbon and the type bars to the printing point to print and means operated by the carriage main spring for repulsing the ribbon guide and ribbon and the type bars away from the printing point after the printing.

9. In a typewriting machine which has its printing point normally in view and the printing ribbon normally away therefrom, the combination of a key, carriage-propelling power, an escapement, and means for bringing the propelling power into action with the escapement to lift the key when the key is depressed and to enable the printing ribbon to start away from the printing point.

10. In a typewriting machine which has its printing point normally in view, and the printing ribbon normally away therefrom, the combination with the keys and carriage propelling power of an escapement having two engaging members which can be disengaged and reengaged, means operated by the keys for disengaging said members, and moving the printing ribbon to the printing point, and means operated by the carriage propelling power for reengaging said members and enabling the printing ribbon to start away from the printing point.

11. In a typewriting machine, the combination with the carriage and carriage propelling power, of a printing ribbon, a key operated escapement mechanism and an escapement roller having its periphery formed into an endless revolving feeding face, means operated by the keys for causing the roller to revolve about its pivot in one direction and for moving the ribbon to the printing point to print, and means operated by the carriage propelling power for revolving the roller about its pivot in the opposite direction and for starting the ribbon away from the printing point.

Signed at Tottenville, borough of Richmond, city and State of New York, this 19th day of April, 1912.

FREDERIC W. HILLARD.
